UNITED STATES PATENT OFFICE.

JOHN L. COBB, OF LOS ANGELES, CALIFORNIA, ASSIGNOR TO AUTOMATIC AIR-LOCK TRAIN-PIPES COUPLERS COMPANY, OF LOS ANGELES, CALIFORNIA, A CORPORATION OF ARIZONA.

COUPLING.

1,173,997.

Specification of Letters Patent. Patented Feb. 29, 1916.

Continuation of application Serial No. 672,006, filed January 12, 1912. This application filed September 11, 1913. Serial No. 789,240.

To all whom it may concern:

Be it known that I, JOHN L. COBB, a citizen of the United States, residing at Los Angeles, in the county of Los Angeles, 5 State of California, have invented new and useful Improvements in Couplings, of which the following is a specification.

This invention relates to improvements in train pipe couplers adapted for coupling 10 either fluid pressure pipes, electrical circuits, or the like, between cars of a train; and this invention consists in various improvements to produce a coupler which is simple of construction and operation, of 15 long wearing qualities and certain of action.

My coupler is particularly adapted for the coupling of train pipe and other fluid pressure pipes and of electrical circuits between the cars of a train; and its mechanism 20 is so arranged that, when the couplers are in engagement, the train pipe air pressure or other fluid pressure, will hold the coupling elements together to form an efficient joint. I am aware of construction in 25 which it has been proposed to use train pipe pressure to hold coupling elements together; but my invention includes not only improvements to render train pipe coupling more efficient, but also to include the possibility 30 of making electrical connections through the same coupler.

Besides numerous minor distinctions there are several fundamental distinctions of my present invention which I wish to herein 35 particularly emphasize.

My improved coupler is formed of a pair of duplicate coupling elements, each including a frame with a flared guide mouth and a tapered guide tongue, the mouths and 40 tongues of the opposing elements adapted to coöperate; and a joint forming member, or pressure carrying box with ports, which is movably mounted upon the frame, and preferably pivoted thereon; and coöperating 45 means on the tongues and on the joint forming members adapted to move the joint forming members away from each other as the tongues and mouths come into their interlocking positions, and adapted to press 50 the joint forming members toward each other at the end of said movement. When the joint forming members are pressed inwardly toward each other, there is a reaction pressure outwardly of the tongues away

from each other and the tongues are thus 55 pressed outwardly so that notches in their outer faces are pressed tightly into engagement with yokes which are carried on the back of the joint forming members. In this manner, the coupling elements are interlocked by mechanical action, and the joint forming members are pressed together by 60 mechanical action; and this is one distinctive feature to which I call attention.

Another distinctive feature to which I 65 call attention is the use of fluid pressure actuated means which acts to press the tongues and the joint forming members apart from each other, acting to press the 70 tongues outwardly and the joint forming members inwardly so that the joint forming members are pressed tightly into engagement with each other and the tongues are pressed outwardly so as to tightly engage 75 their notches with the yokes carried by the joint forming members. Preferably, this part of my apparatus takes the form of diaphragms mounted upon the joint forming members and communicating with the pressure passages therein; so that when 80 pressure is admitted to the coupler it acts directly upon the diaphragms, which press outwardly against the tongues. It will be understood that the diaphragm of each joint forming member presses outwardly against 85 the tongue of the opposing coupling element.

Another fundamental matter of distinction and one which I consider most important, is the manner in which the parts 90 of my coupler are mounted and the manner of connections with the pipes of the train. I have said that the joint forming member is pivoted on the frame member of each coupler element; I also pivotally support 95 the frame on an axis coincident with the axis of the joint forming member; and the pipes are connected to the joint forming member by universal joints (ball and socket joints) which have their centers of movement on the said axis. This construction makes all the parts swing about a single 100 axis, which action at once insures simplicity of movement and a minimum of complications. When the joint forming member moves, it swings about the pivots of the ball joints. When the frame member moves, it also swings about this same pivot; 105

and the movement of neither part can disarrange any of the other parts as all the relatively moving parts are connected together along this one axis.

- 5 There are several other features of great practical importance, among which I may enumerate, (1) the pivotal mounting of the joint forming members, or pressure carrying boxes, upon the respective frames of the 10 coupling element, (2) the means hereinafter described for supporting the coupling element and for connecting them with the pressure pipes so as to afford them sufficient freedom of movement to come into interlocking position regardless of the relative 15 positions of cars or of the car couplings to which they are attached, (3) the exclusion of all springs and all spring devices from the improved coupler, and (4) the 20 general practicability and accessibility of all the parts, including particularly the provision for removal of the joint gaskets without the necessity of uncoupling a train.

With these general features explained, the 25 advantages of various details of construction will be most readily apparent.

I have illustrated preferred forms of my device in the accompanying drawings, in which:

- 30 Figure 1 is a side elevation showing my improved coupler in connected position attached to an ordinary car coupler and to the draw bars of such coupler. Fig. 2 is an enlarged side elevation showing the coupler in 35 connected position with parts in section showing my improved coupler alone. Fig. 3 is a section taken as indicated by line 3—3 of Fig. 2, showing the coupling elements in complete interlocked position. Fig. 4 is a 40 section similar to that of Fig. 3, showing the coupling elements as they appear when moving into their interlocking position. Fig. 5 is a vertical cross section taken as indicated by line 5—5 of Figs. 2 and 3. Fig. 45 6 is a fragmentary view taken as indicated by line 6—6 of Fig. 4 and illustrating the means of withdrawal of the joint gaskets. Figs. 7 and 8 are detail sections showing the construction of the special valve on the train 50 pipe line, such special valve being for the purpose of relieving the pressure which holds the coupling elements together. Fig. 9 is a detail section showing the preferred construction of the longitudinal slip joint in 55 the train brake pipe. Fig. 10 is a section similar to Fig. 4 showing the application of electrical connections in my coupler.

Referring now particularly to the drawings, the numeral 10 may generally designate an ordinary car coupler, the interlocking heads of which are mounted on draw bars 11 of any ordinary construction. It will be understood that the draw bars 11 and the coupler 10 are so placed as to always 65 effect interlocking of the coupler elements

within all possible variations of position, including relative vertical displacement of the two coupler heads; and it will also be understood that my device is hung so that it will properly interlock under all conditions in which the car coupler will interlock. 70

In my improved form of coupler, the various fluid pressure pipes 20, 21 and 22 are all hung from the draw bars 11, in suitable vertical frames 24, wherein there are sliders 25 which allow a certain movement vertically of the pipes to accommodate any necessary vertical movement of the coupling elements. My coupling elements are hung upon vertical ways or frames 26 so as to be allowed a certain limited vertical movement and they are supported directly from the car coupler heads in any preferred manner, such as by having the ways 26 in U-shape, 85 so that the coupler elements may rest upon their bottoms 26^a as is shown in Figs. 2 and 5. I may provide supports 26^b as shown in Figs. 1, 2 and 5. The ways 26 are so mounted upon the car couplers that when the car 90 coupler comes into proper interlocked position, my train pipe coupler will also be in proper interlocked position; and, as herein-after explained, there is provision not only for vertical displacement of the coupler elements, but also for any variation in the extent to which the cars must approach each other in order to be coupled together. 95

Each of my coupler elements includes a frame designated generally by the letter A 100 and a joint forming member designated generally by the letter B. This joint forming member carries the ports and gaskets or electrical contacts which co-engage to couple fluid pressure or electrical circuits between 105 cars of a train. The frame of each element includes a flaring mouth 30 terminating rearwardly in a contracted throat 31, and a tongue 32; and respective guide tongues and guide mouths of opposing elements being adapted to co-operate with each other as is best illustrated in Figs. 3 and 4. The guide tongue of each element is adapted to enter the guide mouth of the other element; and it will be noted that the guide mouths 110 are flared both laterally and vertically and that the tongues are wedge-shaped in a vertical plane; with the general effect that the tongues will enter the mouths within wide limits of divergence of the opposing elements from vertical alignment, and the wedge shape of the tongues will cause the raising of the lower element to the level upon which the uppermost element may be supported. This vertical discrepancy of 115 position may be due to the draw bars and coupler heads hanging slightly higher on one car than on another, or may be due to unevenness of road bed; and in any case, the guide tongues are sufficiently wedge- 120 125 130

shaped to align the opposing elements vertically as they come into their interlocking position.

Each of the frames A is mounted upon a suitable vertical pivot formed by hollow split trunnions 40 having bearings in plates 41 which are adapted to slide vertically in the ways 26. The plates 41 have projecting ears or lugs 41^a which confine them to the guides; but the plates 41 fit loosely in the guides as is best shown in Fig. 3, so that the coupler frames may move slightly to and from each other irrespective of the supporting guide ways 26, and therefore irrespective of the Janney couplers or the draw bars upon which the train pipe coupler is mounted. This looseness of members 41 allows the coupler frames to adjust themselves to each other in a longitudinal direction; that is, to adjust themselves so that their longitudinal axes will be parallel and thus to insure proper interengagements of the two frames. It will be noted particularly from Fig. 2 that the trunnions 40 are hollow and are split longitudinally, being held together by their confinement in the plates 41. The pins 45 prevent the plates 41 slipping off the trunnions; and it is seen to be only necessary to remove the pins 45 when the plates 41 may be removed from the trunnions and the trunnions taken apart to allow the removal of the pivots 46 of the joint forming members B. The joint forming members B are mounted solely upon these pivots 46, concentric with the pivots of the frames; and it will be noted in Figs. 3 and 4 that the joint forming faces 50 of the members B are normally in the plane determined by the vertical axes of the pivots 46. (In Fig. 3 the space between the joint forming surfaces is exaggerated for clarity of illustration.)

The joint forming members B are mounted upon their pivots or trunnions 46 in the hollow trunnions 40 so that the members B are allowed a limited pivotal movement on the frame members A. These members B are preferably provided with one or more fluid pressure passages; in the present case I have shown three fluid pressure passages or compartments 55, 56 and 57, respectively for the signal pipe, the train brake pipe and the steam pipe, (or I may use one or more of these passages for electric conductors). I provide an open space 57^a between the steam and air compartment to insulate the steam compartment from the remainder of the member B and to keep the joint forming gaskets from deterioration by heat. Each of the pipes 20, 21 and 22 connects through the medium of the ball and socket joint 58 with its corresponding passage in the member B; and these passages have ports 59, 60 and 61 leading through the wall of the member

B to the joint forming face 50 thereof, (or, in case of electrical connections, contact heads take the place of one or more of these gaskets). The port 61 for the steam passage is provided with a suitable gasket 62 70 of the general design shown particularly in Fig. 5; while the ports 59 and 60 are provided with suitable gaskets 63 which are carried in removable slides 64 set in the face 50 of member B. The slides 64 75 are of any suitable shape, being preferably dovetailed into member B, so that they may be removed by sliding upwardly without the necessity of uncoupling the coupler elements. The steam passage 57 is provided with a small condensation drainage valve 110 at its lowest point. This valve is preferably a simple cone valve mounted in a removable plug 111 and normally opened by a spring 112, when the steam 85 pressure is released to allow the condensation to drain out. When the steam pressure is turned on, the valve is immediately forced closed.

At this point I wish to call particular 90 attention to the pivoting of the coupler frame and the joint forming member and the universal connection of the pipes with the joint forming member concentrically with said pivots. The drawings show the 95 concentric pivoting of the frames and joint forming members; my preferred construction of hollow trunnions being herein described. And the drawings also show the universal joints with their centers on the 100 single pivot axis. This construction provides for all the parts, one single movement about a common axis; and the fact that this axis is common to all the moving parts makes it possible for any one part to move 105 relatively to any other part without disturbing the general arrangement and without moving any of the other members. Thus the different members and their interconnections and relative movements are 110 reduced to a maximum of simplicity.

On the back side of each member B, the side opposite the joint face 50, I provide a diaphragm 70 shown best in Figs. 3, 4 and 5. These diaphragms are preferably constructed with double diaphragm plates 71 and 72 with a follower plate or disk 73 between them. The whole diaphragm construction is mounted in a plug 74 which is inserted in the outer wall of the member B, 115 so as to be easily removable. My double diaphragm construction provides that no water or dust may reach the inner diaphragm plate 72, thus preserving the diaphragm plate against deterioration which might eventually cause leakage of the pressure from the compartment 56. It will be seen that the outer diaphragm plate 71 is normally flush with the back surface of the member B, while the inner diaphragm plate 120 125 130

is exposed to air pressure in the passage 56. When air pressure is admitted to the coupler, the diaphragms are pressed outwardly as shown in Fig. 3, and the outer plates 72

5 press against the inner face of the tongues 32, having a tendency to press the tongues outwardly and to press the members B in toward each other.

The tongues 32 are each provided with a

10 central longitudinal rib 80 having a notch or depression 81 therein, which notch is adapted to register with a small projecting lip 83 on the yoke bar 84, which yoke bar is carried on the back face of each member B,

15 and spaced therefrom; so that the tongues may enter between the yokes and the back faces of the members B. As the coupling elements come into their interlocking position, the tongues 32 enter the flaring mouths

20 30 and then pass through the throats 31 as illustrated in Fig. 4; thus generally alining the coupling elements and bringing them into correct relative position to accurately interlock. In the position illustrated in

25 Fig. 4, the tongues are just about to enter beneath the yokes 84; and it will be seen that the surfaces 80^a of the lips 80 will engage the lips 83 of the yokes 84; the tongues are thus thrown toward each other

30 and the members B are thrown outwardly away from each other. Throwing the members B outwardly away from each other places the gaskets 63 where they will not strike or rub over each other as the device

35 is coming into final interlocking position. As the elements reach their final positions, shown in Fig. 3, the inner sides of the ends of the tongue 32 ride up over inclined surfaces 86, reaching their final positions just as the

40 notches 81 reach the lips 83; with the effect that the members B are pushed inwardly toward each other, moving on their pivots 46, and the tongues 32 are forced outwardly and the yokes 84 follow the members B in-

45 wardly so that the lips 83 are forced into the notches 81. It will be noted that the lips 83 have beveled shoulders 83^a; and this is for the purpose of allowing the elements B to be pulled apart should they be sub-

50 jected to any great pulling strain, as when a train breaks apart; while under all ordinary conditions, the elements are held together sufficiently tightly to make them one solid and rigid whole. When the elements

55 are interlocked, as shown in Figs. 3 and 5, air pressure is admitted to the passages 56, the diaphragms 70 bulge outwardly and press against the inner faces of the tongues 32. This action presses the tongues tightly

60 into engagement with the yokes 84, pressing the yokes outwardly away from each other and pressing the members B inwardly toward each other. This has the general effect of locking the elements tightly together and

65 pressing the gaskets tightly face to face to

form fluid tight connection between the coupling elements. By relieving the fluid pressure, the elements are easily separable from each other; although, as hereinbefore stated, they may be pulled apart even when the pressure is on by a sufficiently great force. It will be understood that the Janney coupler primarily holds my coupler together; the devices I herein explain are intended merely to hold my coupler elements in interlocked position against accidental displacement, such as by vibration, etc., and to hold the gaskets in tight and proper engagement. It is not intended that my coupler elements should be so tightly locked together that, should the Janney coupler part, any considerable strain would be imparted upon the coupler elements, the train pipes or the various supports. If the Janney coupler parts, my coupler will immediately pull apart. This provision obviates all possibility of broken train pipe or electrical connections which would have to be repaired before the broken train could be again coupled together.

In Fig. 7 I have shown in detail one of the valves 90 which controls the train pipe pressure line 21. The other valves 91 which control the signal pipe and the steam heating pipe are of ordinary construction; but the valve 90 is of special construction to relieve the pressure from the passages 56 and from the diaphragm 70 when the valves 90 are closed, so as to facilitate easy uncoupling of the couplers. The valve 90 has an ordinary body 92, but its plug 93, in addition to the ordinary passage 94 therethrough, is provided with a small bypass 95 which will register with the passage through the body 92 when the valve is turned to its closed position. This bypass 95 leads out to atmosphere through the plug 93; with the effect that the pressure from the coupler compartment 56 will pass back through pipe 21 and through the bypass 95 to atmosphere.

Each of the pipes 20, 21 and 22 has a slip joint 100, and the slip joints 100^a on the air pipe 21 are constructed as is particularly shown in Fig. 9 of the drawings, with pistons 101, the pressure on which tends to press the coupling elements forwardly toward each other. As hereinbefore mentioned, the coupling elements are more or less loosely hung upon the ways 26; and the effect of the slip joints 100^a with their pistons is to press the coupling elements forwardly; thus, a certain amount of longitudinal discrepancy of position is provided for, the coupling elements properly acting if the Janney coupler heads should slightly vary in their approach to each other.

Fig. 10 of the drawings shows how my coupler may be used in effecting electrical connection between coupled cars. Preferably in the upper passage or compartment 130.

55, I place my electric conductors 150 which lead to suitable insulated contact heads 140 mounted in that compartment. These heads may be of any preferred design and 5 may make any desired kind of contact; I have shown a simple head mounted on a stem 141 and pressed forwardly by a spring 142. There may be any desired number of contacts and corresponding number of circuits. When the joint forming members 10 are pressed together the opposing contact heads are pressed together. The action of the coupler is the same as hereinbefore described; the only point of difference being 15 the substitution of electrical circuits and electrical contacts for the fluid pipes and ports.

Having described a preferred form of my invention, I claim:

20 1. In a train pipe coupler, a coupling element, a joint forming member within said coupling element secured to said element by vertical pivots, a pipe secured to said joint forming member by a universal joint, and a longitudinal expansion joint in said pipe, said universal joint being substantially on the pivotal axis of the joint forming member on the coupling element.

25 2. In a train pipe coupler, duplicate coupler elements each comprising a frame forming a guide way having a suitable flared mouth and forming a guide tongue adapted to enter the flared mouth of the other element, a joint forming member pivoted on the frame and having a joint forming side face, a train pipe connected to the joint forming member by a ball joint, a slip joint in the train pipe, there being a passage leading from the ball joint through 30 the joint forming member to said face, and pressure operated members on said joint forming members, said members adapted to press outwardly against the guide tongues and press the said joint forming faces together.

35 3. In a train pipe coupler, joint forming heads connected to the ends of the train pipes by ball joints and having joint forming surfaces on their sides, slip joints in the train pipes, frames pivotally connected to said heads and adapted to meet side face to side face on a line with the pipes, said frames forming guide ways having suitable mouths and guide tongues adapted to 50 enter said mouths, there being passages from the pipes through said heads to the joint forming side faces of the joint heads, yokes carried by said heads for engaging the outer sides of the guide tongues, means carried 55 by said heads for engaging the inner ends of the guide tongues so as to press the guide tongues outwardly and press the joint heads toward each other, and diaphragms extending outwardly from the joint forming 60 heads and communicating with the pres-

sure ports, so that when the pressure is turned on the diaphragms will press outwardly against the guide tongues and press the joint heads together.

4. In a train pipe coupler, a coupler member having a flaring mouth and a contracted throat, a parallel guide plate at one side in such a position that it will enter the throat of an opposing coupler member, a pivoted member within the coupler member having compartments therein and ports leading therefrom laterally so that the ports of opposing couplers coincide with each other, and means for bringing the contact faces of the pivoted members into intimate contact with each other.

5. In a train pipe coupler, a coupler member having a flaring mouth and a contracted throat, a parallel guide plate at one side in such a position that it will enter the 70 throat of an opposing coupler member, the outside of the guide plate having a depression, a pivoted member within said coupling member having compartments therein and ports leading therefrom laterally so that the 75 ports of opposing couplers register with each other, a bar on the outer side of the pivoted member provided with a tongue which is adapted to enter the depression in the guide plate of an opposing coupler member, 80 and means for bringing the contact faces of the pivoted members of opposing couplers into contact with each other.

6. In a train pipe coupler, a pair of coupling members, comprising interlocking frames and joint forming members movably mounted thereon, and fluid pressure operated means carried by each joint forming member and adapted to press against the interlocking frame of the other coupling 100 member to press the joint forming members together.

7. In a train pipe coupler, a pair of coupling members, comprising interlocking frames and joint forming members pivotally mounted thereon, and fluid pressure operated means carried by each joint forming member and adapted to press against the interlocking frame of the other coupling member to press the joint forming members 105 together.

8. In a train pipe coupler, a pair of duplicate coupling members, comprising interlocking frames, joint forming members pivotally mounted thereon and having ports 120 adapted to register with each other, and cooperating means on the frames and joint forming members for holding the members apart as the coupling members come into interlocking position and to allow the members to come together when in interlocking 125 position.

9. In a train pipe coupler, a pair of duplicate coupling members, comprising interlocking frames having guide mouths and 130

guide tongues adapted to enter the mouths, pressure carrying boxes pivoted on the frames having ports adapted to co-register, coöperating means on the frames and boxes 5 for holding the boxes apart as the coupling members come into interlocking position and to allow the boxes to come together when in interlocking position, and fluid pressure operating means on the boxes and 10 each pressing against the tongues of the other coupling member to press the boxes together.

10. In a train pipe coupler, duplicate elements each comprising an outer pivotal member, a member within pivoted to the outer member, the inner member having conduits therein to receive pressure fluid and ports in a lateral face of said member, and means for holding said lateral faces 15 apart from each other until they are in position to be locked together.

11. In a train pipe coupler, an outer pivotal member, a member within pivoted to the outer member, the inner member having 20 therein conduits to receive fluid pressure and adapted to have their inner surfaces contact with each other, ports in the opposing contact faces which communicate with the ports of a similar coupler, means for 25 holding the contact faces from sliding contact while the opposing members are moving together, and means operating at the final longitudinal movement of the opposing couplers to bring the contact faces together by 30 a lateral movement.

12. In a train pipe coupler, an inner and an outer member pivotally mounted together the inner member having contact surfaces and pressure fluid conduits leading to said 40 contact faces with communicating ports through said contact faces, the outer member having a contact surface, normally on a vertical longitudinal line with the contact surface of the inner member, the outer 45 member having an open flaring mouth and a guide way to one side of the contact surface, and a guide plate to the other side of the contact surface, said guide plate being wedge-shaped, so that it will enter the flaring 50 mouth of the similar opposing coupler and vertically center the opposing ports of the inner member.

13. In a coupler, a pair of duplicate coupling elements comprising interlocking frames, joint forming members movable thereon, and means carried by each frame and member of the duplicate element adapted to co-engage to keep the said members apart during the interlocking movement of the frames and to positively force the said members together at the end of said movement by virtue of said movement.

14. In a coupler, a pair of duplicate coupling elements each comprising a frame and 60 a joint forming member movable thereon,

each frame including a guide mouth and a corresponding guide tongue, means on each joint forming member to engage the outer face of the guide tongue of the other coupling element to hold the said members apart during the interlocking movement of the elements, and means on each joint forming member to engage the inner face of the guide tongue to force said members together at the end of said movement. 75

15. In a coupler, a pair of duplicate coupling elements each comprising a frame and a joint forming member movable thereon, each frame including a guide mouth and a corresponding guide tongue, a yoke on each joint forming box, the guide tongue of the opposing coupling element adapted to pass between the yoke and the said member, there being a notch in the outer face of each tongue adapted to receive the corresponding yoke, and an inclined surface on the face of each joint forming member adapted to engage the corresponding tongue to press the member away from the tongue. 80

16. In a coupler, a pair of duplicate coupling elements each comprising a frame having a guide mouth and a corresponding guide tongue, a joint forming member pivoted on said frame, said member having a joint forming surface adapted to be pressed together, a yoke carried by each member spaced from its side opposite the joint forming face, the space between the yoke and said side lying near the guide mouth of the corresponding frame so that when the guide 90 tongues enter the guide mouths, the guide tongues enter said yoke spaces, and inclined surfaces on said sides of the joint forming members over which the ends of the tongues are adapted to ride, the tongues having 95 notches adapted to register with the yokes when their ends ride over the said inclined surfaces. 100

17. In a coupler, a pair of duplicate coupling elements each comprising a pivotally supported frame, said frames adapted to interlock, a joint forming member pivoted on an axis coincident with the axis of the frame pivot, and means for forcing said joint forming members toward each other when 110 the frames are interlocked. 115

18. In a coupler, a pair of duplicate coupling elements each comprising a pivotally supported frame, said frames adapted to interlock with each other, a joint forming member pivotally supported on the frame on an axis coincident with the frame axis, and universal joint connection with the joint forming member, said universal joint having 120 its center on said pivot axis of the frame and joint forming member. 125

19. In a coupler, a pair of duplicate coupling elements each comprising a frame pivotally supported on a vertical axis, vertically 130 slidably supporting means for said axis, a

joint forming member pivotally supported on said frame on an axis coincident with the frame axis, said joint forming member having fluid passages therethrough and having 5 ports on its face opposing the other joint forming member, universal joint connection for a train pipe to the joint forming member, said universal joint having its center of movement on said axis of the frame and 10 the joint forming member.

20. In a coupler, a pair of duplicate coupling elements each comprising a pivotally supported frame, said frames adapted to interlock by movement longitudinally toward 15 each other, a joint forming member pivoted on an axis coincident with the axis of the frame pivot, each joint forming member having a joint forming face normally in the plane determined by the said axis and parallel 20 to the longitudinal interlocking movement of the frames, and means for forcing said joint forming members toward each other when the frames are interlocked.

21. In a train pipe coupler, a pair of duplicate coupling elements each comprising a frame pivotally supported upon a vertical axis, said frames adapted to interlock by movement toward each other in the plane of their axes, a joint forming member pivoted 30 on the frame concentrically with the frame axis and having a joint forming surface normally in the plane of said axes, coöperating means on the frames and members to hold said members transversely apart during 35 their movement toward each other, and means to force said members transversely together.

22. In a train pipe coupler, a pair of duplicate coupling elements each comprising a frame pivotally supported upon a vertical axis, said frames adapted to interlock by movement toward each other in the plane of their axes, a joint forming member pivoted 40 on the frame concentrically with the frame axis and having a joint forming surface normally in the plane of said axes, there being fluid passages through said member and ports in its joint forming surface, universal 45 train pipe connection with the joint forming member having its center of movement in said vertical axis, coöperating means on the frames and members to hold the said members transversely apart during their movement toward each other, and means to force 50 said members transversely together.

23. A train pipe coupling, comprising a coupler head, a pivoted air box mounted thereon, connections from said air box to suitable source of pressure supply, and 60 means for forcing said air box laterally into engagement with a similar box adapted to be operated by means on the coöperating coupler.

24. A train pipe coupler, comprising a 65 hanger, a head slidably mounted therein, a

pivoted air box mounted in said head and secured therein, said air box being provided with a plurality of chambers having two series of ports, pivotal connections from one of said series of ports, connecting the 70 chambers to suitable sources of fluid under pressure, slidable connections interposed in said connections, inclosing walls in said head to limit the movement of said air box, and means to positively operate said air box 75 when coupled to insure a complete operable contact.

25. A train pipe coupling, comprising a hanger, a head movably mounted therein provided with guiding lugs having bores 80 and a plurality of walls terminating in a flaring hood, and also forming an inclosure, a guide arm adapted to enter the hood of an adjoining head, an apertured air box mounted in said inclosure and pivoted in 85 said bores, and means to force said box in contact with an adjoining box when the apertures therein register.

26. A train pipe coupling, comprising a hanger, a head slidably mounted therein 90 provided with a plurality of apertured chambers, and oppositely disposed guiding lugs on the top and bottom of said head, having side walls connecting the top and bottom of said head, one of said walls being extended and tapered to form a guiding arm, the oppositely disposed wall having an outward disposed end forming one side of a guiding hood, a plurality of partition walls intermediate of said side walls forming a recess, one of said walls having a flaring end 95 forming a deflector for said recess and hood; an air box pivotally mounted in said recess, and means to operate said box to swing in said recess. 105

27. In a coupler, a pair of inter-engaging coupler elements each carrying a frame, a vertical pivot for said frame, a movable joint forming member mounted in the frame, and mountings for the upper and lower ends of the vertical pivot allowing relative horizontal movements of the upper and lower ends of said pivot so that the frames may adjust themselves to each other when interlocking. 110

28. In a coupler, a pair of inter-engaging coupler elements carrying a frame, a vertical pivot for said frame, a movable joint forming member mounted in the frame on said vertical pivot, and mountings for the upper and lower ends of the vertical pivot allowing relative horizontal movements of the upper and lower ends of said pivot so that the frames may adjust themselves to each other when interlocking. 120

29. In a coupler, a pair of inter-engaging coupler elements carrying a frame, a vertical pivot for said frame, a movable joint forming member mounted in the frame, fluid pressure means carried by each joint 130

- forming member to press against the frame of the other member to press the joint forming members together, and mountings for the upper and lower ends of the vertical pivot allowing relative horizontal movements of the upper and lower ends of said pivot so that the frames may adjust themselves to each other when interlocking. 30
30. In a coupler, a pair of inter-engaging 10 coupler elements each embodying a frame, a vertical pivot for said frame, a movable joint forming member mounted in the frame on said vertical pivot, train pipes connected to said joint forming members by universal 15 joints arranged substantially on the axis of said vertical pivot, and mountings for the upper and lower ends of the vertical pivot allowing relative horizontal movements of the upper and lower ends of said pivot so 20 that the frames may adjust themselves to each other when interlocking.
31. In a coupler, a pair of inter-engaging 20 coupler elements each embodying a frame, a vertical pivot for said frame, a movable joint forming member mounted in the frame on said vertical pivot, train pipes connected to said joint forming member by universal 25 joints arranged substantially on the axis of said vertical pivot, longitudinal expansion
- 35 joints in said pipes, and mountings for the upper and lower ends of the vertical pivot allowing relative horizontal movements of the upper and lower ends of said pivot so that the frames may adjust themselves to each other when interlocking. 30
32. In a coupler, an element embodying a frame, a joint forming member pivoted thereto on a transverse pivot having a lateral joint forming surface, and means for forcing said member laterally about its pivotal mounting into engagement with a joint forming surface of another element. 35
33. In a coupler, an element embodying a frame, a pivotal mounting for the frame embodying transverse vertical pivot, a joint 40 forming member in the frame pivotally mounted on said pivot having a lateral vertical joint forming surface, and means for forcing said member laterally about its pivotal mounting into engagement with a joint 45 forming surface of another element. 50

In witness that I claim the foregoing I have hereunto subscribed my name this 12th day of August, 1913.

JOHN L. COBB.
